CIRCUIT CONTROLLING DEVICE FOR STEAM GENERATORS

Filed Dec. 6, 1927

UNITED STATES PATENT OFFICE

ABRAHAM SHAPIRO, OF BROOKLYN, NEW YORK

CIRCUIT-CONTROLLING DEVICE FOR STEAM GENERATORS

Application filed December 6, 1927. Serial No. 238,063.

This invention relates generally to heating devices, and has more particular reference to a novel circuit controlling device therefor.

cally connected by wires 21 to a power transformer, 53, the primary of which connects to a variable rheostat 54, a switch 55, and leads 56 to some source of current.

5. This invention has for an object the provision of an electric device capable of generating hot water and steam for the heating of radiators or the like and provided with the circuit controlling means.

The modified form of steam generator illustrated in Figs. 4 and 5 discloses the generator 15' provided with supporting feet 22 and a circular heating unit 23 therein. The boiler is split and fastened together at 24. The wires 25 connect the heating unit to some source of current. 55 60

10 Another object of the invention is the provision of an electric device of simple efficient construction, which can be manufactured and sold at a reasonable cost.

A rod 26 is pivotally mounted at its upper end to the top of each of the steam generators, as at 27, and a spring 28 normally urges the rod into vertical position against the stop 29 from the boiler. The rod 26 has a longitudinal dove-tailed groove 30 with serrations 31 at its base, and slides 32 and 33 engage in the groove. Each of these slides has extensions 34 threadedly engaged by 70

For further comprehension of the invention and of the objects and advantages thereof, reference will be had to the following description and accompanying drawings and to the appended claims in which the various novel features of the invention are more particularly set forth.

screws 35 abuttable against the serrations 31 to hold the slides as set. Slide 32 has a pair of contacts 36 connected by wires 37 to a high water alarm device, or the like, not shown in the drawing, so that the height of water 18 may be maintained below the high water mark. Likewise, slide 33 has a pair of contacts 38 connected by wires 39 to a low

Referring to the accompanying drawing forming a material part of this disclosure:

water alarm device, or the like, not shown on the drawing, so that the height of water 18 may be maintained above the low water mark. When the top of either generator is removed, the rod 26 may be swung to one side against the action of spring 28 allowing more room for the adjustment of the slides 32 and 33. 80 8*

Fig. 2 is a central sectional view taken on the line 2-2 in Fig. 1.

The operation of the device consists in energizing the heating coils to heat the water 18, producing steam which flows through pipes 16 to the radiators 12. 90

Fig. 4 is a view similar to Fig. 2 but illustrating a modified form of steam generator provided with the same invention.

While I have illustrated and described the preferred form, construction and arrangement of the several elements employed, it will be understood that the device is nevertheless, susceptible of considerable modification therein, and I therefore reserve the right and privilege of resorting to all such changes as may be fairly embodied within the spirit and scope of the invention as claimed. 95 100

Fig. 6 is a fragmentary vertical sectional view, taken on the line 6—6 of Fig. 5. The reference numeral 10 indicates the floor, and 11 the walls of a room having customary steam radiators 12. A base 13 rests on the floor 10 and supports a heat insulating member 14 and a boiler 15 thereon. Pipes 16 starting at the top or steam portion of the generator connect with the radiators. A water injector pipe 17 leads water 18 within the generator. The generator is provided with a safety valve 50, a steam pressure gauge 51, and a water level indicating tube 52.

A plurality of electrical heating coils 19
50 projecting from a platform 20 are electri-

Having thus described my invention, what I claim as new and desire to secure by United States Letters Patent is:

1. In an electrically heated steam generator, a boiler arranged for electrically generating steam, and having a removable top, a rod pivotally mounted within the boiler at its upper end and on the top of the boiler and extending down to near the bottom of the boiler, and arranged for supporting a circuit closing means, a stop projecting from the said boiler top, and a spring urging the said rod against the stop for normally holding the rod in a vertical position, and permitting said rod to be swung to one side against the action of the spring for providing more room for the adjustment of a circuit closing means supported by the said rod.
2. In an electrically heated steam generator, a boiler arranged for electrically generating steam, and having a removable top, a rod pivotally mounted within the boiler at its upper end and on the top of the boiler and extending down to near the bottom of the boiler, and arranged for supporting a circuit closing means, and means for normally holding the rod in a vertical position, and permitting said rod to be swung to one side for providing more room for the adjustment of a circuit closing means supported by the said rod.

In testimony whereof I have affixed my signature.

ABRAHAM SHAPIRO.
